UNITED STATES PATENT OFFICE

CHARLOTTE ELIZABETH APPLEBEE, OF CHICAGO, ILLINOIS

WINDOW PROTECTIVE DEVICE

Application filed August 21, 1930. Serial No. 476,774.

This invention relates to a window protective device, and the object of the invention is the provision of an improved device of heavy screen construction adapted to be inserted 5 in a window or similar building opening for protection against entry by all intruders. A further object is the provision of a device of this character which is conveniently inserted or removed in a window so as to be of a de- 10 tachable nature and which effectively serves as a protective burglar-proof screen or the like, and also as a protection against persons or objects falling through a window or building wall opening. An additional object is the 15 provision of an efficient detachable window protective device, durable and efficient in use, and economical to manufacture.

Other objects will appear hereinafter.

The invention consists in the combinations 20 and arrangements of parts hereinafter described and claimed.

The invention will be best understood by reference to the accompanying drawings, forming a part of this specification, and in 25 which:

Fig. 1 is an elevational view, taken from the exterior of a window, showing the device in operative position;

Fig. 2 is an enlarged vertical sectional view, 30 taken substantially on the line 2—2 of Fig. 1;

Fig. 3 is an enlarged transverse sectional view, with parts broken away, taken substantially on the line 3—3 of Fig. 1;

Fig. 4 is a vertical sectional view from the 35 interior of the window, showing the device mounted in position, and taken on a vertical plane substantially between the parting stops of the window frame and the device of the invention;

Fig. 5 is a sectional view, taken substantially on the line 5—5 of Fig. 4;

Fig. 6 is a sectional view, taken substantially on the line 6—6 of Fig. 5, showing the 45 locking member in position;

Fig. 7 is a detail view of a modified form of the lower extremity of the locking member;

Fig. 8 is a sectional view, taken substantially on the line 8—8 of Fig. 7;

Fig. 9 is a plan section, taken substantially on the line 9—9 of Fig. 7; and

Fig. 10 is a detail elevational view of the upper portion of the meeting edges of the two members composing the device.

As illustrated in the drawings, the preferred embodiment of the invention is adapted to be inserted below the upper window sash and between the window frame parting stops and blind stops, although the device is not necessarily restricted to this particular installation. This manner of mounting effectually prevents unauthorized entry and serves as a protective device from the interior of the building as well, while allowing free movement of the inner window sash.

As illustrated in Fig. 1, looking from the exterior, the preferred construction comprises a right hand member 12 and a left hand member 13 which are identical in general construction except for the arrangement at the central meeting edges. Each of the members 12 and 13 comprises a vertically extending flat plate 14 adapted to be inserted and extend between the parting stop and the blind stop of a window. The upper extremity of each plate 14 is turned inwardly to provide a flange 15, and the lower extremity similarly provides an inturned flange 16; and the ends of a vertically extending rod 17 are pivotally mounted respectively on the inturned portions 15 and 16. Rod 17 serves as a support for an upper transverse sash member 18 and a lower transverse sash member 19.

The opposite or inner extremities of the sash members 18 and 19 of the unit 12 are secured to a vertically extending sash member 20, and similarly the inner extremities of the sash members 18 and 19 of the units 13 are secured to a vertically extending sash member 21. These parts may be riveted, bolted, or otherwise securely fastened in such manner that each unit 12 and 13 is adapted to swing relative to the attached plate 14.

A plurality of relatively heavy meshing covers each of the units or members 12 and 13, and for this purpose it is preferred to employ steel or metal rods of relatively heavy stock such as one-eighth inch in diameter for adequate protective purposes, which are

designated at 22. The vertically extending rods are secured to the transverse sash members 18 and 19 either by welding or riveting of the ends, and similarly the transverse or 5 horizontally extending rods are secured respectively to the appropriate vertical sash member 20 or 21, and also to the rod 17, the latter connection being either by welding or by the provision of a securely engaging loop 10 formed on the transverse rods. Also, as a further protective insurance the vertically extending rods adjacent the central meeting edges of the two units are preferably disposed closer together than the remainder and 15 also, if preferred, the horizontally extending rods adjacent the opening for the reception of the locking member presently described, are also disposed closer together than the remaining rods. Thus each unit 12 and 13 presents 20 a heavy screen member requiring considerable force in the employment of instruments to mutilate. As shown in Fig. 3, the sash members 20 and 21 are rectangular in general cross-sectional outline, and in installation the respective plates 14 are disposed in position and the two members are then simultaneously drawn inwardly, so that there is practically a forced fit when the two members are pulled into alignment to assume a vertical 25 position across the window.

Sash member 21 is provided with an outer laterally extending plate 23 adapted to overlie the outer surface of member 20 on the adjacent unit, and is also provided with an inner flange 36 spaced a slight distance from the main sash portion 21. Similarly, the member 20 is provided with a flange 25 spaced from the sash 20. The inner edges of the flanges 24 and 25 are also preferably spaced apart a slight distance, and when the units are positioned in 40 place as described, the flanges 24 and 25 form, with the sash members 21 and 20, a vertically extending socket or slot for the reception of a locking member. To facilitate introduction and removal of the locking member, the flanges 24 and 25 do not extend entirely 45 throughout the height of members 21 and 20, but are terminated to provide spaces 26 and 27 and relatively short flanges 28 and 29, identical with flanges 24 and 25 in construction, are formed adjacent the upper extremities of the sash members 20 and 21, respectively.

The locking member 30 is composed of a 50 plurality of hinged sections which may be secured by pivot pins as shown to provide smooth pivotal connections. These sections are preferably of flat steel for making a tight fitting engagement within the vertically extending socket described, and the locking member or strip 30 is of sectional formation to facilitate introduction and withdrawal through the openings 26 and 27. Thus member 30 may be composed of sections 31 and 32, each slightly less in length

than is provided by openings 26 and 27, and of short sections 33, 34, 35, and 36. A compression spring 37 is preferably connected to sections 34 and 35, as shown in Fig. 6. To assemble the device in locking position, after 55 the units 12 and 13 have been aligned as described, locking member 30 is inserted downwardly through openings 26 and 27 until the lowermost section 36 contacts with the window sill, after which spring 37 is compressed until section 33 is lowered for insertion through openings 26 and 27. The strip is then released and expansion of spring 37 forces section 33 upwardly between the upper flanges 28 and 29 to the position 80 shown in Fig. 6, which effectually locks the two units in place. To facilitate manipulation of the locking member a knob or handle 38 may be mounted on the section 31.

As an additional means for locking the device in place, the lowermost section 36 may be provided with a downwardly depending projection 39, as shown in Fig. 7, for extension within a socket provided in the lower window sill, or a more efficient engagement 85 may be afforded by mounting a keeper plate 40 on the window sill. Keeper plate 40 is provided with a central opening 41 for the reception and engagement of projection 39, and may be secured by screws 42.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A window protective device of the character described, comprising a pair of plate members arranged to be inserted between the parting stops of a window frame, a pair of screen units pivotally connected, respectively, to said plate members to allow the free vertical edge portions of said units to be brought into abutting relationship, an inner vertical flange member mounted upon each of said free vertical edge portions and spaced therefrom, and a locking member arranged to be inserted in the space between said vertical flange members and said vertical edge portions.

2. A window protective device of the character described, comprising a pair of plate members arranged to be inserted between the parting stops of a window frame, a pair of screen units pivotally connected, respectively, to said plate members to allow the free vertical edge portions of said units to be brought into abutting relationship, an inner vertical

flange member mounted upon each of said free vertical edge portions and spaced therefrom, a locking member arranged to be inserted in the space between said vertical flange members and said vertical edge portions, and an outer plate mounted upon one of said vertical edge portions and adapted to overlie the other vertical edge portion.

3. A window protective device of the character described, comprising a pair of plate members arranged to be inserted between the parting stops of a window frame, a pair of screen units pivotally connected, respectively, to said plate members to allow the free vertical edge portions of said units to be brought into abutting relationship, an inner vertical flange member mounted upon each of said free vertical edge portions and spaced therefrom, a locking member arranged to be inserted in the space between said vertical flange members and said vertical edge portions, and means upon said locking member for engaging said window frame.

4. A window protective device of the character described, comprising a pair of plate members arranged to be inserted between the parting stops of a window frame, a pair of screen units pivotally connected, respectively, to said plate members to allow the free vertical edge portions of said units to be brought into abutting relationship, an inner vertical flange member mounted upon each of said free vertical edge portions and spaced therefrom, a locking member arranged to be inserted in the space between said vertical flange members and said vertical edge portions, an outer plate mounted upon one of said vertical edge portions and adapted to overlie the other vertical edge portion, and means upon said locking member for engaging said window frame.

In testimony whereof I have signed my name to this specification.

CHARLOTTE ELIZABETH APPLEBEE.
